UNITED STATES PATENT OFFICE

92,299

DESIGN FOR A STOVE

Christopher L. Hardwick, Cleveland, Tenn.

Application December 20, 1933, Serial No. 50,148

Term of patent 3½ years

To all whom it may concern:

Be it known that I, CHRISTOPHER L. HARDWICK, a citizen of the United States, residing at Cleveland, county of Bradley, and State of Tennessee, have invented a new, original, and ornamental Design for a Stove, of which the following is a specification, reference being had to the accompanying drawing forming part thereof.

The figure is a perspective view of a stove showing my design.

I claim:

The ornamental design for a stove as shown.

CHRISTOPHER L. HARDWICK.
